UNITED STATES PATENT OFFICE

126,395

DESIGN FOR A BOTTLE POURER

Rose R. Hoffman, Philadelphia, Pa.

Application May 28, 1940, Serial No. 92,667

Term of patent 3½ years

To all whom it may concern:

Be it known that I, Rose R. Hoffman, a citizen of the United States, residing at Philadelphia, the county of Philadelphia and State of Pennsylvania, have invented a new, original, and ornamental Design for a Bottle Pourer, of which the following is a specification, reference being had to the accompanying drawing, forming part thereof,

Fig. 1 is a top perspective view of a bottle pourer showing my new design; and

Fig. 2 is a perspective view showing the article in a different position.

I claim:

The ornamental design for a bottle pourer, as shown,

ROSE R. HOFFMAN,
